UNITED STATES PATENT OFFICE.

DELOSS H. STEPHENS, OF RIVERTON, CONNECTICUT.

DESIGN FOR A DESK-RULE.

SPECIFICATION forming part of Design No. 14,043, dated July 3, 1883.

Application filed May 17, 1883. Term of patent 7 years.

To all whom it may concern:

Be it known that I, DELOSS H. STEPHENS, a citizen of the United States, residing in Riverton, Litchfield county, Connecticut, have invented a Design for a Desk-Rule, of which the following is a specification.

My design for a desk-rule is fully illustrated by the perspective view in the accompanying drawing.

10 The rule A has the usual beveled and graduated edge, *a*; but instead of having flat upper and lower surfaces each of the latter has two longitudinal grooves, *b b*, which may, if desired, be colored, so as to be distinct from the 15 remainder of the rule.

I claim—

The design for a desk-rule, the same being of a shape similar to that of an ordinary rule of this class, but ornamented by longitudinal grooves, as shown and described. 20

In testimony whereof I have signed my name to this specification in the presence of two subscribing witnesses.

DELOSS H. STEPHENS.
